UNITED STATES PATENT OFFICE.

JAMES S. KINGSTON, OF OTTAWA, ONTARIO, CANADA.

FIRE-HOSE BRIDGE.

Application filed June 28, 1922. Serial No. 571,397.

To all whom it may concern:

Be it known that I, JAMES SAMUEL KINGSTON, a citizen of Canada, and a resident of Ottawa, in the Province of Ontario, Dominion of Canada, have invented a new and Improved Fire-Hose Bridge (for which I have filed an application in Canada February 13th, 1922, Patent No. 263,583), of which the following is a full, clear, and exact description.

It is one of the objects of this invention to provide means whereby at the time of a fire in a building situated on the line of a street railway or other vehicular traffic that a fire hose can be attached to a fire hydrant, fire plug or fire engine, situated on the opposite side of the street or road to that on which the building is on fire, in such a manner that the railway or other vehicular traffic will not be stopped owing to fire hose laying across the surface of said railway or road.

It is a further object of this invention to construct a device of this character in such a member that it may be quickly put into action by men of a fire brigade and as quickly removed.

With this and other objects in view, the invention consists essentially in the novel construction and arrangement of parts hereinafter more fully described and illustrated by the accompanying specification and drawings.

Referring to the drawings, in which like characters of reference indicate corresponding parts in each figure.

Figure 1 is a side elevation of the device in upright position.

Figure 2 is a similar view of the device in lowered position.

Figure 3 is a detail view of the hinge joint.

In the drawings Y represents the trolley wires, my device consisting of a metal standard E designed to support and carry a tubular section P adapted to form the cross arm of the hose bridge and provided at each end with male and female hose threads M. The section P is made preferably of brass, copper or steel piping and may be provided with a covering of rubber or other suitable material to insulate it from the trolley wires. I is a supporting member for the section P fixedly secured thereto at the top end by means of a plate bolted on the member P substantially midway of its length and

fixedly secured to the member I. N are sockets formed on the member I adapted to support the braces J provided with clamps O to embrace the section P and fully secured thereon by bolts R.

From the foregoing it will be seen that the hose section P and short supporting member I form one complete section which is designed to fit into a socket F in the top of the standard E to be securely held thereby means of a set screw lever G.

Having dealt with the upper end of the standard E, the lower end or base is provided with a hinge or movable joint U for the purpose of attaching or detaching it. This joint is formed with a notch or pocket X in the moving and stationary parts and is designed to engage with the pivotally mounted dog V on the standard E, the dog being provided with an operating handle W.

This section is composed of a brass, copper, iron or steel pipe of a suitable internal diameter, and in cases where the same is used where overhead electric trolley wires are in use, is covered or insulated with rubber or other suitable material as a precaution against contact with electric wires through careless handling.

On each end of hose bridge P. P. is fixed a male or female hose thread denoted by M. preferably on an obtuse angle.

This hose section is secured permanently and centrally to a section denoted by I. of standard E. by a clamp in two halves and bolted thereto, and is denoted by letter R.

The weight of hose bridge or section P. P. is supported by wrought iron braces J. J. secured into sockets N. N. on section I. and bolted onto collars O. O. at the required distance on P. P. permanently. Thereby making the hose bridge and short section I. one complete section of my said fire hose bridge.

The end of section I. is inserted into socket F. on standard E. and is held fast therein by set screw lever G. Eye ring on collar H. on standard E. is for the purpose of attaching a rope used to pull fire bridge standard into a vertical position, also for lowering same.

In connection with this improved fire hose bridge a cast iron box, or socket, of square shape, having a heavy iron cover lined with a rubber ring for the purpose of keeping out water, is sunk permanently on the center of a street, or road, denoted by

A. opposite to a fire hydrant, fire plug, or fire engine, and is denoted by B. The depth of this socket, or metal box, to be to suit the material of which the surface of road, 5 or street, is made.

The short standard or section denoted by C. is of suitable height above ground line and made of approved metal, one end of 10 which is square to fit into the metal box, or socket, denoted by B. The top end of section C. is round or cylindrical.

The device is operated in the following manner. Section C. is placed in socket B, the tail end of standard E. is placed inside 15 the top of section C. The collar a short distance from end of standard E. resting on collar or flange on the top of section C. Set screw lever D. is then made tight. The weight of standard E. being borne by portable standard Q.

Fire hose bridge section P. P. is then placed in a vertical position but leaning slightly towards standard E. and is connected to standard E. by the short section I. 20 and secured in socket F. by set screw lever G.

A rope is secured to eye-ring denoted by H. on standard E. for the purpose of pulling standard E. into a perpendicular position assisted by firemen raising standard E. 25 and water bridge P. P.

The clutch or locking bar denoted by V. will then fall into slots or pockets X. cut on hinge U. and be secured therein by set 30 screw lever W. when standard E. is in a perpendicular position.

The fire hose section P. P. now being parallel with the line of road or street, or with the railway rails, set screw lever V. 35 on section C. is loosened.

Iron or hardwood levers denoted by S. S. are inserted into sockets T. T. on the section C. and standard E. is turned on the previously described flanges by the firemen, so 40 that the fire hose section P. P. will lay transversely to the car rails, street or line of traffic, and above the line of street car trolley wires, thereby allowing a line of up and down vehicular traffic to pass under 45 same. Set screw lever V. is then made tight. Fire hose is then connected to the male or female threads on end of section P. P. by drawing a brigade latter truck under same.

The wrought iron portable stand to be 55 used only during erection or removal.

In cases where fire hydrant, fire plug or engine has more than one outlet for fire 60 hose, two or more of the cast iron boxes are to be sunk in road bed in front of each other or at any suitable distance from each other for the erection of more than one fire hose bridge.

Furthermore, by the construction shown and described, the entire device may be 65 erected or dismantled in three sections and any one section easily handled by the men of a fire brigade, and transported to and from a fire on a brigade latter truck.

Having now particularly described and 70 ascertained the nature of my said invention, and in what manner the same is to be performed what I do claim as my invention and desire to secure by Letters Patent is—

1. A fire hose bridge comprising in combination with socket means in the ground a pedestal formed with a socket, a removable standard adapted to fit into the pedestal and provided with a hinge joint, a top supporting member designed to fit into the standard and a tubular cross member formed with 75 hose threaded ends secured to said supporting member, means for locking the supporting members and the standard and means for locking the hinge joint and means for 80 turning the standard member around.

2. The combination with a fire hose bridge, of a socket or box of suitable metal built into a street or road, a suitable standard, a detachable section of fire hose supported centrally on top of said standard, and suitable means for locking or securing 85 the several sections of said fire hose bridge.

3. A device of the character described in combination with a ground socket, a standard having a hinge joint and adapted at one end to fit into a supporting member adapted at the other end to receive a support, a hose section, means for locking the standard member and the section members 90 and means for turning the standard members.

Ottawa, Canada, June 24th 1922.

JAMES S. KINGSTON.

Signed in the presence of—

ERNEST E. V. MONTANDON,
J. W. WHITTINGHAM.
